RAILWAY CAR

Eber W. Light, Charleston, W. Va., assignor to
 Sanford Investment Corporation, Knoxville,
 Tenn., a corporation of Delaware

Application June 21, 1926, Serial No. 117,505

23 Claims. (Cl. 105—364)

This improvement relates particularly to mine cars and cars for similar use.

The object of this invention is to produce such a car of sufficient strength by the use of materials which are less costly than the materials put into some of the better class mine cars.

A leading feature of the present construction is the use of strong steel side sills without metal end structures connecting the ends of the side 10 sills, the end bumpers being supported by the car bottom. This permits placing the bumper structure lower than is the case when the end structure is joined to the ends of the side sills. In the present structure the bottom is also placed 15 low, whereby the load is brought close to the rails. By placing the bumper structure on the car bottom, easy discharge is provided when the car is tilted endwise for discharge from one end of the car.

20 The above-mentioned structural features and other structural features will be described hereinafter.

In the accompanying drawings,

Fig. 1 is a side elevation of a car embodying 25 my improvement, parts being broken away;

Fig. 2 is a plan of the same car, parts being broken away;

Fig. 3 is a bottom view of the same car;

Fig. 4 is an upright section on the line, 4—4, 30 of Figs. 2 and 3;

Fig. 5 is a front elevation;

Fig. 6 is an upright section on the line, 6—6, of Fig. 1, looking toward the left;

Fig. 7 is an upright section on the line, 7—7, 35 of Fig. 1, looking toward the left;

Fig. 8 is an upright section on the line, 8—8, of Fig. 1, looking toward the left;

Fig. 9 is an upright section on the line, 9—9, of Fig. 1, looking toward the left;

40 Fig. 10 is an upright longitudinal section through the rear end of the car, the section being similar to the left hand part of Fig. 4, with a hanger added above the axle;

Fig. 11 is an elevation of the rear end of the 45 car;

Fig. 12 is an upright longitudinal section similar to Fig. 4, a fixed end wall being substituted for the gate at the right hand or forward end of the car, and certain other details being changed, 50 this form of the car being adapted for sidewise turning for discharging the load.

Referring to the drawings, R, are track rails. A, A are track wheels on which the car is supported. A1, A1 are axles which are supported 55 by the wheels. The axles extend through the

side sills, B, B. In the form shown in the drawings, these sills are steel channels having outward directed flanges, B1. In each channel is a bearing block, B2, which forms a bearing or rest for the axles.

The space between the side sills, B, is filled with planks, C, C, placed horizontally and lengthwise of the car and below the axles.

Binders, C1, extend transversely under and against the lower faces of the planks and the 10 lower faces of the lower side sill flanges, B1, and thence upward across the outer sides of the side sills and over filling blocks, C2. Bolts or rivets, C3, extend horizontally through the binders of the filling blocks and the upright web of 15 the side sills.

A sheet metal side plate, D, has one edge resting on the upper flange, B1, of each side sill and extends thence horizontally outward and then upward. The binders extend horizontally outward and against the lower face of each side plate and then upward along the outer face of the upright part of the side plate. Rivets, D1, extend through the side plates and the binders and through the horizontal part of the side plate 20 and the upper flange of the side sill. (See Figs. 6, 7 and 8). Rivets, C4, extend through the planks, C, and the binders, C1. (See Figs. 1, 2, 3, 4 and 7).

The ends of the bottom planks, C, project 30 beyond the car body far enough to form parts of the bumper structure. Short or supplemental plank pieces, E, are placed flatwise on the upper faces of the plank, C, at each end of the car, the outer ends of the pieces, E, being even 35 with the adjacent ends of the planks, C. These supplemental plank pieces form a part of the bumper structure. A metal bumper cap, E1, extends over the ends of the planks, C and E, and is secured to said planks by means of upright 40 bolts or rivets, E2. Bolts or rivets, E3, extend through the planks, E and C, and the adjacent binder, C1, whereby said planks and the binder are firmly secured to each other. The planks, E and C, are further joined to each other by 45 means of the metal coupling tongue, F, resting on the planks, E, and rivets, F1, extending through said tongue and said planks. The inner part of said tongue is shown spread into V-form so as to lie on each of the three planks, E and C, which are shown as forming supplemental planking and the bottom of the car between the side sills.

The tongue, F, rises and extends outward above the cap, E1, and is spaced above said cap far 55

enough to admit a coupling link, F2. The outer end of the tongue and the cap, E1, are apertured on a common upright line to receive a coupling pin, F3. By means of the binders, C1, and the rivets, C4, and the rivets, E3, the bottom planks, C, are well secured to the side sills; and the bumper structure is formed in part of the ends of the bottom planks and is supported by said planks and not on the side sills.

10 It will now be observed that the bumper structure heretofore supported by the end sills and along with the side sills, forming a rectangular frame, is absent.

15 At the forward end of the car (the right hand end as shown in Figs. 1, 2, 3 and 4) an end gate or door, G, extends across the space above the bumper structure and the forward ends of the side sills, B, and the side plates, D, the middle part of the lower edge of said door being notched 20 at G1 to make room for the coupling tongue, F. A U-form strap, G2, extends horizontally across the upper part of the face of said gate and over the end edges of said gate and across the adjacent binder, C1, and horizontally to the next binder, C1, and between said binder and a brace, G3. A pintle, G4, extends through the brace, G3, and the strap, G2, and the binder, C1, and the side plate, D. Thus the end gate or door is hinged to permit it to rest on the bumper structure or 30 to be lifted for the discharge of the load of coal or other material from the car when the car is tilted forward in the tipple. A second U-shape strap, G5, extends horizontally across the outer face of the door immediately above the coupling 35 tongue, F, and thence rearward across the adjacent binder, C1, and obliquely upward to the lower edge of the strap, G2. There a splicing plate, G6, extends across the adjacent end of the strap, G5, and the strap, G2, and is secured to 40 said straps by means of rivets, G7. Above the coupling tongue, F, an upright hook plate, G8, extends across the straps, G5 and G2, and is secured to said straps and the door by means of rivets, G9. The upper end of said plate is bent 45 forward and downward to form a hook adapted to be engaged by a bar or similar member on a tipple for supporting the door while the forward part of the body of the car is lowered in a tipple, as is well known in this art.

50 At the forward end of the car, the rear ends of the short planks, E, have their upper faces made slanting to meet the upper face of the bottom planks, C. This is for the purpose of permitting easy forward sliding of the contents of 55 the car when the car has been tilted.

To permit easy forward movement of the material, forming the load, over the axles, A1, a hood or deflecting plate, H, is placed over each 60 axle and extended from one side sill to the other, the part of the hood at the rear of the axle being slanted sufficiently to produce such easy moving or sliding. Forward of the axle, the hood may extend downward abruptly. The forward 65 edge of the hood rests on the upper face of the planks, C, and is secured to said planks by means of rivets, H1. The rear edge of each of these hoods rests on the upper face of the floor planks above the adjacent binder, C1, and is secured to the planks by means of the adjacent rivets, C4, said rivets in this case extending through 70 the hood, the planks and the binders. At each end each hood has an upward directed flange, H2, resting against the adjacent upright web of the side sill and secured thereto by rivets, H3.

75 Fig. 4 of the drawings shows each of said hoods

as making contact with the adjacent axle, A1, so that said hoods form an additional means of supporting the plank floor bottom. But it will be observed that these hoods are so formed as to make lateral clearance and avoid lateral engagement with the axles. The purpose of this is to preclude strain on the axles tending to bend them if excessive endwise thrust or strain is placed on the bumper structure and the bottom planks whereby the planks tend to shift 10 endwise by straining the binders, C1, and the riveting by which the binders are secured to the planks.

In Fig. 10, a hood is applied as in Fig. 4, and a hanger, H4, is placed under the hood and across the axle and has its ends resting on the planks and secured thereto by means of bolts or rivets, H5. That hanger is shown resting on the axle to form additional supporting means for preventing downward movement of the plank bottom; but the hanger is made wide enough to make lateral clearance and avoid engagement with the axle in case there is such accidental endwise movement of the plank bottom as has been mentioned above. In Fig. 12 these hangers are applied the same as in Fig. 10, but the hood, H, is omitted, that car being intended to be turned sideways for discharging, tipples of the rotary type being designed for that operation. It is to be understood that the hangers, H4, may be of any 30 desired number.

Each track wheel, A, rises higher than the horizontal part of the side plates, D. Hence each wheel must penetrate said side plate. Hence the horizontal part of the side plate is provided with an aperture, D2. A hood, D3, is seated on each side plate above each wheel. Adjacent the upright part of the side plate, the hood has an upturned flange, D4, which is secured to said part of the plate, D, by means of rivets, D5. The inner 40 part of each hood consists of a segment wall, H6, which is secured to the plate, D, and the main part of the hood by means of rivets, D6, and the forward part of each hood is shown concentric with the adjacent part of the wheel, A, while the rear 45 part of the hood is made slanting to such extent as to facilitate sliding of material forward across the hood when the car is tilted for discharging the load.

It is to be observed that the main bottom, the 50 part of the bottom between the side sills, is below the axles, hence this is a low bottom car. It is also to be observed that the bumper structure is low, reaching above the upper face of the plank bottom only as much as the thickness of the short 55 supplemental planks, E; and those planks, as already described, are made slanting to facilitate discharge of the load. This arrangement permits discharging the load without tilting the car to the extent that would be required if a higher bumper 60 structure or a higher end sill structure were placed between the side sills.

The metal side sills give ample support to prevent sagging of the load. At the same time the use of the planking for the bottom and as parts 65 of the bumper structures provides lower cost for a given load capacity than is provided by an all-metal car.

I claim as my invention,

1. In a railway car of the kind described, the 700 combination of metal side sills, axles supporting the side sills, wheels on the axles, a plank bottom between the side sills below the axles and extending beyond the ends of the side sills, binders extending under and secured to the plank bottom 750

- and to the side sills, and a bumper and coupling structure at each end of the plank bottom, substantially as described.
2. In a railway car of the kind described, the combination of metal side sills, axles supporting the side sills, wheels on the axles, a plank bottom between the side sills below the axles and extending beyond the ends of the side sills, binders extending under and secured to the plank bottom and secured to the side sills, and a bumper and coupling structure, including supplemental planking, at each end of the plank bottom, substantially as described.
3. In a railway car of the kind described, the combination of metal side sills, axles supporting the side sills, wheels on the axles, a plank bottom between the side sills below the axles and extending beyond the ends of the side sills, binders extending under and secured to the plank bottom and secured to the side sills, and a bumper and coupling structure, including supplemental planking and a bumper cap and a coupling tongue, at each end of the plank bottom, substantially as described.
4. In a railway car of the kind described, the combination of channel metal side sills, axles supporting the side sills, wheels on the axles, filling blocks on the side sills, a plank bottom between the side sills below the axles and extending beyond the ends of the side sills, binders extending under and secured to the plank bottom and the side sills and filling blocks, and a bumper and coupling structure at each end of the plank bottom, substantially as described.
5. In a railway car of the kind described, the combination of metal side sills, axles supporting the side sills, wheels on the axles, a plank bottom between the side sills and extending beyond the ends of the side sills, binders extending under and secured to the plank bottom and to the side sills, a bumper and coupling structure at each end of the plank bottom, an end door, and hoods extending across the axles and secured to the planking, substantially as described.
6. In a railway car of the kind described, the combination of metal side sills, axles supporting the side sills, wheels on the axles, a plank bottom between the side sills and extending beyond the ends of the side sills, binders extending under and secured to the plank bottom and to the side sills, a bumper and coupling structure at each end of the plank bottom, and hoods extending across the axles and secured to the planking and having lateral clearance at the axles substantially as described.
7. In a railway car of the kind described, the combination of metal side sills, axles extending through the side sills, wheels on the axles, a plank bottom between the side sills and extending beyond the ends of the side sills, binders extending under and secured to the plank bottom and to the side sills, and a bumper and coupling structure at each end of the plank bottom, substantially as described.
8. In a railway car of the kind described, the combination of metal side sills, axles supporting the side sills, wheels on the axles, a plank bottom between the side sills below the axles and extending beyond the ends of the side sills, binders extending under and secured to the plank bottom and to the side sills, a bumper and coupling structure including a slanting supplemental planking, and an end door, substantially as described.
9. In a railway car of the kind described, the combination of metal side sills, axles supporting the side sills, wheels on the axles, a plank bottom between the side sills below the axles and extending beyond the ends of the side sills, binders extending under and secured to the plank bottom and to the side sills, a bumper and coupling structure including a slanting supplemental planking, an end door, and slanting hoods extending over the axles, substantially as described.
10. In a railway car of the kind described, the combination of metal side sills, axles supporting the side sills, wheels on the axles, a plank bottom between the side sills and extending beyond the ends of the side sills, binders extending under and secured to the plank bottom and to the side sills, a bumper and coupling structure at each end of the plank bottom, and hangers extending over the axles and having clearance at the sides of the axles and secured to the plank bottom, and hoods extending over the hangers, substantially as described.
11. In a railway car of the kind described, the combination of metal side sills, axles supporting the side sills, wheels on the axles, a plank bottom between the side sills below the axles and extending beyond the ends of the side sills, binders extending under and secured to the plank bottom and to the side sills, and a bumper and coupling structure including an apertured bumper cap and apertured coupling tongue, substantially as described.
12. In a railway car of the kind described, the combination of metal side sills, axles supporting the side sills, wheels on the axles, a plank bottom between the side sills below the axles and extending beyond the ends of the side sills, side plates supported by the side sills, binders extending under and secured to the plank bottom and to the side sills and to the side plates, and a bumper and coupling structure at each end of the plank bottom, substantially as described.
13. In a railway car of the kind described, the combination of metal side sills, axles supporting the side sills, wheels on the axles, a plank bottom between the side sills and extending beyond the ends of the side sills, binders extending under and secured to the plank bottom and the side sills, hangers extending over the axles and having clearance at the side of the axles and secured to the plank bottom, and a bumper and coupling structure at each end of the plank bottom, substantially as described.
14. In a railway car of the kind described, the combination of metal side sills, axles supporting the side sills, wheels on the axles, a bottom consisting of a plurality of planks between the side sills below the axles and extending beyond the ends of the side sills, binders extending under and secured to the plank bottom and to the side sills, and a bumper and coupling structure comprising supplemental planking and a bumper cap and a coupling tongue having its base extending over and secured to the supplemental planking and a plurality of the bottom planks, substantially as described.
15. In a railway car of the kind described, the combination of metal side sills, axles supporting the side sills, wheels on the axles, a bottom consisting of a plurality of planks between the side sills below the axles and extending beyond the ends of the side sills, binders extending under and secured to the plank bottom and to the side sills, a bumper and coupling structure comprising supplemental planking and a bumper cap and a coupling tongue having its base extending over

and secured to the supplemental planking and a plurality of the bottom planks, and one of the binders, substantially as described.

16. In a railway car of the kind described, the combination of metal side sills, axles supporting the side sills, wheels on the axles, a bottom below the axles and extending beyond the ends of the side sills, a bumper and coupling structure at each end of the bottom, and a door extending across the space above the floor and between the side sills at one end of the car, substantially as described.

17. In a railway car of the kind described, the combination of metal side sills, axles supporting the side sills, wheels on the axles, a bottom below the axles and extending beyond the ends of the side sills, a bumper and coupling structure comprising a coupling tongue and seated on the bottom, and a door extending across the space above the floor and between the side sills and being notched to receive the coupling tongue, substantially as described.

18. In a mine car, sills, wheel axles, ties between said sills, a longitudinal buffer beam supported on said ties and located below the wheel axles, and coupler members connected to said buffer beam.

19. In a mine car, sills, wheel axles, ties between said sills, a longitudinal buffer beam supported on said ties and located below the wheel axles, and housings for the wheel axles above said buffer beam, said housings being connected to said sills.

20. In a mine car, sills, wheel axles, ties between said sills, a floor having a longitudinal buffer beam supported on said ties and located below the wheel axles, coupler members connected

to said buffer beam, and housings for the wheel axles, said housings having a gradual slope towards one end of the car for preventing the housings interfering with the dumping of the car contents.

21. In a mine car, wheel axles, sills, ties connecting said sills, a longitudinal buffer beam supported on said ties below the wheel axles and forming a portion of the floor, wooden flooring extending from the buffer beam to the sills, a filler block mounted on and above the end of the buffer beam and flooring, and a bumper carried by the flooring and mounted on said filler block.

22. In a railway car of the kind described, the combination of metal side sills, car axle journals whose axes lie in a horizontal plane which cuts the side sills, wheels on the axle journals, a plank bottom between the side sills and under the horizontal plane of the axes of the axle journals and extending beyond the ends of the side sills, binders extending under the plank bottom and secured to the side sills, and a bumper and coupling structure at each end of the plank bottom.

23. In a railway car of the kind described, the combination of metal side sills, car axle journals whose axes lie in a horizontal plane which cuts the side sills, wheels on the axle journals, a central bottom between the side sills and under the horizontal plane of the axes of the axle journals and extending beyond the ends of the side sills, binders extending under the central bottom and secured to the side sills, and a bumper and coupling structure at each end of the central bottom.

EBER W. LIGHT.
